[57] CLAIM

The ornamental design of a damper unit, as shown and described.

DESCRIPTION

FIG. 1 is a perspective view of the damper unit showing our new design.

FIG. 2 is a top plan view thereof.

FIG. 3 is a bottom plan view thereof.

FIG. 4 is an end elevational view thereof, the opposite end being a mirror image of the end shown.

FIG. 5 is a left side elevational view thereof.

FIG. 6 is a right side elevational view thereof.

FIG-1

FIG-2

FIG-3

FIG-4

FIG-5

FIG-6

UNITED STATES PATENT AND TRADEMARK OFFICE
CERTIFICATE OF CORRECTION

PATENT NO. : Des. 271,615

DATED : November 29, 1983

INVENTOR(S) : John Prikkel, III

It is certified that error appears in the above-identified patent and that said Letters Patent are hereby corrected as shown below:

Under References Cited:

1st Reference: Insert ---,III--- after "Prikkel".

2nd Reference: "1,337,904" should be ---1,337,907---.

11th Reference: Insert ---,III--- after "Prikkel".

12th Reference: Insert ---,III--- after "Prikkel".

Signed and Sealed this

Third Day of April 1984

[SEAL]
